US00D632821S

(12) **United States Design Patent**
Culbert

(10) **Patent No.:** **US D632,821 S**
(45) **Date of Patent:** **** Feb. 15, 2011**

(54) **LED LIGHT FIXTURE**

(75) Inventor: **J. Scott Culbert**, Birmingham, AL (US)

(73) Assignee: **Glowble SSL, Inc.**, Birmingham, AL (US)

(**) Term: **14 Years**

(21) Appl. No.: **29/343,896**

(22) Filed: **Sep. 21, 2009**

(51) **LOC (9) Cl.** **26-05**

(52) **U.S. Cl.** **D26/74**

(58) **Field of Classification Search** **D26/72, D26/74, 75, 76, 77, 78, 79, 80, 81, 82, 83, D26/84, 85, 86, 88, 89, 90, 91, 1, 2, 3, 24, D26/56; D13/180, 182; 362/555, 576, 147, 362/150, 217.01, 219, 217.02, 217.03, 217.04, 362/217.05, 217.08, 217.09, 260, 364, 365, 362/366, 404, 800**

See application file for complete search history.

(57) **CLAIM**

The ornamental design for an LED light fixture, as shown and described.

DESCRIPTION

FIG. 1 is a top perspective view of the LED light fixture.
FIG. 2 is a top view of the LED light fixture of FIG. 1.
FIG. 3 is an end view of the LED light fixture of FIG. 1.
FIG. 4 is a side view of the LED light fixture of FIG. 1.
FIG. 5 is a bottom view of the LED light fixture of FIG. 1; and, FIG. 6 is a bottom perspective view of the LED light fixture of FIG. 1.
